ROLL GRINDER

Application filed September 25, 1928. Serial No. 308,254.

This invention relates to roll grinders and more especially to improvements in the operating mechanisms thereof.

It is particularly important that the support for grinding wheels and other operating mechanisms be rigid and free from the possibility of movement after having been set in their operative positions. In many instances, it is also required that the grinding wheel be adjustable into a number of different positions relatively to the work.

Relatively long rolls require considerable time to grind and being of considerable weight, are cumbersome and difficult to set up in the grinding machine. It is desirable to completely grind these rolls wherever such work is required on the machine where the roll is originally set up so that all the surfaces ground will be concentric or otherwise properly related to each other. A machine capable of performing all of the grinding operations required upon a roll, without readjusting or resetting the roll, greatly increases the accuracy of the finished product and reduces the cost of the same by a considerable saving in labor and time.

This invention contemplates the provision of a grinding machine wherein a roll may be accurately ground on its periphery and have its ends ground at an angle to its peripheral surface, beveled or rounded as desired, without readjusting or resetting the work relatively to the grinding wheel.

One of the objects of this invention is to provide an improved roll grinding machine.

Another object of this invention is to provide in a grinding machine an improved grinding wheel supporting structure.

Another object of this invention is to provide a swivel grinding wheel support.

Still another object of this invention is to provide a grinding wheel support which will be provided with means to feed the grinding wheel axially along, toward and away from, and be swingable relatively to, the work mounted in the work support.

A further object of this invention is to provide novel and improved means for feeding and swiveling the grinding wheel of a roll grinding machine relatively to the work

mounted therein, and which will operate efficiently and without affecting the rigidity and relative position required between the wheel and the work.

To these and other ends, our invention consists in the novel features and combinations of parts to be hereinafter described and claimed.

In the accompanying drawings:

Fig. 1 is a plan view of a machine embodying the features of this invention;

Fig. 2 is a front elevation of the machine;

Fig. 3 is a section on line 3—3 of Fig. 1;

Fig. 4 is a top plan view of the grinding wheel supporting structure;

Fig. 5 is a section on line 5—5 of Fig. 4;

Fig. 5^A is a partial section on line 5^A—5^A of Fig. 5;

Fig. 6 is a top plan view of the grinding wheel supporting structure moved into a different position than that shown in Fig. 4, and in which certain parts have been omitted for the sake of clearness;

Fig. 7 is a top plan view of a grinding wheel supporting structure of somewhat modified form;

Fig. 8 is a front elevation of the same, and

Fig. 9 is a section on line 9—9 of Fig. 7.

The grinding machine selected to illustrate the features of this invention, generally comprises a frame 10, upon which is mounted suitable work supports comprising a power driven head stock 11 and an adjustable tail stock 12. A tool carriage 13 is provided and mounted upon suitable guideways 14 and 15, secured or formed upon the frame 10.

The carriage 13 is adapted to be reciprocated upon the guideways 14 and 15 in an axial direction relatively to the work mounted between the work supports. Suitable power operated means 16 is provided and mounted upon the carriage 13 to reciprocate it. The reciprocating means 16 generally comprises a motor 17, a train of gears 18, including reversing mechanism, and a driven pinion 19, which cooperates with a stationary rack 20, secured to the frame 10.

A grinding wheel supporting structure is also provided and mounted upon the carriage 13. In this instance, two grinding wheels 21 and 22 are provided and mounted upon the

common shaft 23, which is rotated by means of an electric motor 24, through the medium of a belt 25, and suitable pulleys 26 and 27 respectively mounted upon the motor shaft 5 and shaft 23. The shaft 23 is journaled in a wheel base 28. The wheel base 28 is mounted upon a sub-base 29, which in turn is mounted upon the carriage 13.

- In this instance, the wheel base 28 is pivotally mounted on the sub-base 29 and therefore the grinding wheels are swingable relatively to the work, and the axis thereof may be disposed at any angle to the axis of the work which is desired. Mechanism for swiveling the base 28 is provided and mounted thereon. The base 28 is pivoted to the sub-base 29 at 30 by the cooperation between a stud 31 on the sub-base 29 with a roller bearing 32, secured within an opening 26 in the base 28. A plurality of annular engaging surfaces 33 and 34 are respectively formed upon the base 28 and sub-base 29 to support the base upon the upper surface of the sub-base 29.
- 25 An annular rack 35, concentric to the pivot point 30 is provided and is secured upon the periphery of the sub-base 29. In mesh with the teeth of the rack 35 is a pinion 36 mounted upon the end of a vertical shaft 37, which is journaled in a bearing 38, secured to the base 28. A worm wheel 39 is secured to the upper end of shaft 37, the teeth of which are in mesh with a worm 40, secured upon a horizontal shaft 41.
- 35 The shaft 41 passes into a clutch or gear box 42, being journaled in the bearing 43 therein, and is keyed to a clutch member 44. One end of a clutch sleeve 45 is adapted to cooperate with clutch member 44 to engage the same. The clutch sleeve 45 is rotatably mounted partly upon an end extension 46 of the shaft 41 and partly upon the end extension 47 of a shaft 48, which is in alignment with shaft 41, and also passes into and is journaled in the box 42 in a bearing 49. A bevel gear 50 is keyed to the clutch sleeve 45, the sleeve being adapted to slide axially relatively to this gear and upon the shaft end extensions 46 and 47, so as to permit an operative connection between the same and the clutch member 44, to drivingly connect the gear 50 thereto. A bevel pinion 51 is in driving engagement with the gear 50. The pinion 51 is mounted upon a shaft 52, which is an extension of the shaft of an electric motor 53. The motor 53 is mounted upon the wheel base 28. A handwheel 54 is secured upon the motor shaft 52 to permit manual rotation thereof when this is desired.
- 60 The other end of the clutch sleeve 45 is adapted to engage a clutch member 55 keyed upon the shaft 48. Both of the clutch members 44 and 55 are suitably retained against axial movement by means of thrust bearings 56 and 57 respectively, which are secured to

opposite sides of the gear box 42, which houses the aforesaid parts. The clutch sleeve 45 may be reciprocated to operatively engage either clutch member 44 or 55, or to be disposed in a neutral position out of engagement with either. A clutch lever 58, through the medium of a vertical shaft 59 and links 60, which engage trunnions provided upon an operating ring 61, which is mounted upon the sleeve 45, may be operated to slide the sleeve 45 into any of the aforesaid positions.

The sub-base 29, in this instance, is slidably mounted upon the carriage 13, being slidably supported thereon by the cooperation between suitably formed guides 62 and guideways 63, respectively formed upon the sub-base 29 and carriage 13. In the arrangement shown, the sub-base 29 is slidable upon the carriage 13 in a direction transverse to the axis of the work and substantially at 85 right angles to the direction of the reciprocating movement of the carriage 13.

To obtain the aforesaid transverse sliding movement of the sub-base 29, the following mechanism is provided. A lead screw 64 is secured to the carriage 13 and retained thereon against rotation. The screw 64 extends beneath the sub-base 29 and is disposed with its axis parallel with the guides 62 and guideways 63. A sleeve nut 65, journaled in a lug 66, secured to and depending from the sub-base 29 is adapted to threadingly engage the screw 64. A bevel gear 67 is mounted upon and secured to the nut 65, with its teeth in mesh with a pinion 68.

The pinion 68 is secured upon the lower end of the vertical shaft 69, which is journaled in the sub-base 29 and extends upwardly through the stud 31, concentric with the axis of the pivot point 30, between the base 28 and sub-base 29. A bevel gear 70 is secured to the upper end of the shaft 69, and is in driving engagement with a bevel pinion 71, pinned to the shaft 48, which extends into a gear box 72, being journaled in a thrust bearing 73 therein. The gear box 72 houses the gear 70 and pinion 71 as well as providing a bearing for a handwheel shaft 74, which extends into the box at an angle with the axis of the shaft 48, and is connected thereto by means of a universal joint coupling 75.

A hand-wheel 76 is secured to the outer end of shaft 74, to permit the manual operation of the nut 65, upon the screw 64, to slide the sub-base 29 upon the carriage 13.

By means of the reciprocable feeding movement provided for the carriage 13, it is obvious that the grinding wheel may be moved axially with respect to the work in either direction. By means of the above described mechanism for transversely feeding the sub-base 29, the grinding wheels may be moved transversely with respect to the axis of the work, and by means of the above described mechanism for swinging the wheel

base 28 with respect to the sub-base 29, the grinding wheel may be swiveled relatively to the work into the position shown in Fig. 6, or into any intermediate position as desired. The two latter movements may be obtained either manually or by power, by proper manipulation of the clutch sleeve 45. Preferably, power is applied for coarse and fast adjustments and the hand-wheels used to manually obtain fine adjustments.

Fig. 6 illustrates one use for which the swivel arrangement for the grinding wheel may be put. In this case, one of the grinding wheels is being used to grind the end surface of a roll. It will be obvious that if the base 28 is only partially swung about its pivot 30 relatively to the sub-base 29, a bevel of any desired angle can be ground upon the end of the roll, and that in a machine of this type, by keeping the grinding wheel in contact with the peripheral surface of the roll up to its end, and then swinging the wheel base 28 upon its pivot, while backing up the sub-base, a rounded corner might be formed. Preferably, however, a formed wheel would be used when forming a rounded corner, the wheel being set at an angle and fed against the corner. It is also to be noted that any and all of these operations may be performed without disturbing the original setting of the roll between the supports therefor, and that, therefore, the time and labor consuming operations of resetting the roll for these different operations has been eliminated and that accuracy in the location and form of the cuts made will be assured.

Figs. 7, 8 and 9 illustrate a somewhat modified form of mechanism for obtaining the same results. In this instance, a sub-base 80 is provided with internal teeth formed upon a ring segment 81, secured thereto. A gear 82 secure upon a shaft, is in driving engagement with the ring segment 81, and is in turn driven by a chain of gearing 83, including a worm wheel 84 and worm 85. The worm 85 is secured to the shaft of the motor 86. Operation of this mechanism will rotate the wheel base 87 upon a pivot 88, disposed between the same and the sub-base 80. A feed screw 89, journaled in the sub-base 80, and rotated by means of a worm wheel 90 and worm 91, which is secured upon the shaft of a motor 92, cooperates with the threads 93 provided in the lug 94, secured upon the carriage 95 to slide the sub-base 80 transversely thereof.

As in the previously described form, the sub-base 95 is slidable upon frame 96 by suitable mechanism operating through a pinion 97, which is in driving engagement with the rack 98, secured to the frame 96. Grinding wheels 99 and 100 are mounted upon the wheel base 87, and driven by means of motor 101, by the use of a belt 102.

While we have shown and described a pre-

ferred embodiment of our invention, it is understood that it is not to be limited to all of the details shown, but is capable of modification and variation, which will lie within the spirit of the invention and the scope of the appended claims.

What we claim is:

1. In a grinding machine, a frame, work supports, a grinding wheel adapted to operate upon work in said supports, means to cause said grinding wheel to traverse the work axially thereof, means to move said wheel toward and away from the work transversely of the axis thereof, and means to swing said grinding wheel into a position wherein its axis is at an angle to the axis of the work, a source of power, and means to connect and disconnect either of said two last named means to said source of power.

2. In a grinding machine, a frame, a carriage reciprocably mounted upon said frame, means to reciprocate said carriage longitudinally of said frame, a sub-base slidably mounted upon said carriage for movement in a direction transverse to the direction of the movement of said carriage with respect to said frame, and a grinding wheel base pivotally mounted upon said sub-base, and common power means to move said sub-base relatively to said carriage, and to rotate said wheel base upon said sub-base.

3. In a grinding machine, a frame, a carriage reciprocably mounted upon said frame, means to reciprocate said carriage longitudinally of said frame, a sub-base slidably mounted upon said carriage for movement in a direction transverse to the direction of the movement of said carriage with respect to said frame, and a grinding wheel base pivotally mounted upon said sub-base, and common power means mounted on said wheel base to move said sub-base relatively to said carriage and to rotate said wheel base upon said sub-base, and means to connect said power means to the respective part to be moved, and to disconnect the other part therefrom.

4. In a grinding machine, a reciprocable carriage, a sub-base slidably mounted upon said carriage, a grinding wheel base pivotally mounted upon said sub-base and common means to move said sub-base and swing said wheel base upon its pivot.

5. In a grinding machine, a reciprocable carriage, a grinding wheel base mounted upon said carriage for sliding and pivotal movement relatively thereto, and common means to selectively slide and swing said wheel base.

6. In a grinding machine, a reciprocable carriage, a sub-base slidably mounted upon said carriage, a grinding wheel base pivotally mounted upon said sub-base, common means to move said sub-base on said carriage and to swing said wheel base upon its pivot, and additional means to move said sub-base

- on said carriage when said common means is disconnected therefrom.
7. In a grinding machine, a reciprocable carriage, a grinding wheel base mounted upon said carriage for sliding and pivotal movement relatively thereto, and means selectively operable to slide said wheel base or to swing the same.
8. In a grinding machine, a reciprocable carriage, a grinding wheel base mounted upon said carriage for sliding and pivotal movement relatively thereto, and power operated means selectively operable to slide said wheel base or to swing the same.
9. In a grinding machine, a reciprocable carriage, a grinding wheel base mounted upon said carriage for transversely sliding movement relatively thereto and for lateral swinging movement relatively to said carriage, means selectively operable to slide or swing said wheel base, and power actuated means and manually operable means selectively operable to actuate said first means.
10. In a roll grinding machine, means to rotatably support and rotate a roll, a carriage mounted to reciprocate axially with respect to the roll, a sub-base mounted upon said carriage to slide transversely relatively to the axis of the roll, a grinding wheel support mounted to swing in a horizontal plane, means to slide said sub-base, and means to swing said wheel support, both of said means being mounted on said wheel support, a common power drive for said last two mentioned means, and means to selectively connect said power drive with either of said means.
11. In a roll grinding machine, means to rotatably support and rotate a roll, a carriage mounted to reciprocate axially with respect to the roll, a sub-base mounted upon said carriage to slide transversely relatively to the axis of the roll, a grinding wheel support mounted to swing in a horizontal plane, means to slide said sub-base and means to swing said wheel support, both of said means being mounted on said wheel support, a common power drive for said last two mentioned means, and means to selectively connect said power drive with either of said means, and manually operable means to slide said sub-base when said common power drive is disconnected therefrom.
12. In a roll grinding machine, means to rotatably support and rotate a roll, a carriage mounted to reciprocate axially with respect to the roll, a sub-base mounted upon said carriage to slide transversely relatively to the axis of the roll, a grinding wheel support mounted on said sub-base to swing in a horizontal plane, an electric motor mounted on said wheel support, and means to operably connect said electric motor with said sub-base to slide the same, and operably connect with said wheel support to swing the same,
- said means operably disconnecting said motor from one when connecting it to the other.
13. In a roll grinding machine, means to rotatably support and rotate a roll, a carriage mounted to reciprocate axially with respect to the roll, a sub-base mounted upon said carriage to slide transversely relatively to the axis of the roll, a grinding wheel support mounted on said sub-base to swing in a horizontal plane, an electric motor mounted on said wheel support, and means to operably connect said electric motor with said sub-base to slide the same, and to operably connect said motor with said wheel support to swing the same, said means operably disconnecting said motor from one when connecting it to the other, and means to slide said sub-base independently of said motor.
14. In a grinding machine, a carriage, a sub-base slidably mounted on said carriage, a grinding wheel base pivotally mounted on said sub-base, means to swing said wheel base relatively to said sub-base disposed above said sub-base, and means to slide said sub-base upon said carriage disposed below said sub-base, means disposed above said sub-base to operate said swinging and sliding means, and means passing through said sub-base to operably connect said operating means with said sliding means.
15. In a grinding machine, a carriage, a sub-base slidably mounted on said carriage, a grinding wheel base pivotally mounted on said sub-base, means to swing said wheel base relatively to said sub-base disposed above said sub-base, and means to slide said sub-base upon said carriage disposed below said sub-base, means disposed above said sub-base to operate said swinging and sliding means, and means passing through the pivot point between said sub-base and said wheel base to operably connect said operating means with said sliding means.
16. In a grinding machine, a carriage, a sub-base slidably mounted on said carriage, a grinding wheel pivotally mounted on said sub-base, means to slide said sub-base including a shaft, means to swing said grinding wheel including a shaft, and rotatable means mounted partly on each shaft and shiftable axially thereof in one direction to drive one shaft, and in the other direction to drive the other shaft.
17. In a grinding machine, a carriage, a grinding wheel mounted upon said carriage for sliding and swinging movements relatively thereto, means to slide and means to swing said grinding wheel, each of said means including a shaft, and rotatable means mounted partly on each shaft and shiftable axially thereof in one direction to drive one shaft and in the other direction to drive the other shaft.
18. In a grinding machine, a carriage, a sub-base slidably mounted on said carriage, a

grinding wheel base pivotally mounted on said sub-base, means to swing said wheel base relatively to said sub-base including a shaft, and means to slide said sub-base upon said carriage including a shaft, means to operate said swinging and sliding means, and means passing through said sub-base to operably connect said operating means with said sliding means, said operating means including 5 rotatable means mounted partly on each of said shafts and shiftable axially thereof in one direction to drive one shaft, and in the other direction to drive the other shaft.

In witness whereof, we have hereunto set 10 our hands this 22nd day of September, 1928.

RICHARD C. LEWIS.
CARL F. SCHNUCK.
